UNITED STATES PATENT OFFICE.

EDWIN E. ANGELL, OF BOSTON, ASSIGNOR OF ONE-HALF TO E. B. WELCH, OF CAMBRIDGE, MASSACHUSETTS.

CAN-HEADING MACHINE.

SPECIFICATION forming part of Letters Patent No. 415,993, dated November 26, 1889.

Application filed February 18, 1889. Serial No. 300,249. (No model.)

To all whom it may concern.

Be it known that I, EDWIN E. ANGELL, of Boston, in the county of Suffolk and State of Massachusetts, have invented certain new and useful Improvements in Can-Heading Machines, of which the following is a specification.

This invention relates to machines for applying flanged heads to sheet-metal can-bodies; and it has for its object to provide a simple and effective machine adapted to perform the operation of applying said heads without attention from an operator other than the insertion of the heads into the holders which present them to the can-bodies.

The invention consists in the several improvements which I will now proceed to describe and claim.

Of the accompanying drawings, forming a part of this specification, Figure 1 represents a side elevation of my improved machine. Fig. 2 represents an end elevation of the same. Fig. 3 represents a longitudinal section. Fig. 4 represents a section on line $x x$ of Fig. 3.

In the drawings, a represents a chute, through which can-bodies are fed to the mechanism which applies the flanged heads to the ends of the can-bodies, said bodies having been previously formed into cylindrical shape, and soldered by suitable mechanism—for example, such as is shown in prior applications for improvements in can-soldering machines filed by me. The cans are allowed to drop one at a time from the chute by a feeding mechanism, hereinafter described, upon a movable support or arm b , which is mounted to swing on a fixed rod or support e , attached to the frame of the machine, and is operated by a cam, hereinafter described, so as to stand under the chute a and between the can-body clamps $c c$ in position to arrest and support a can-body dropping from the chute until the said clamps clasp the can-body, and then move away, so as to be out of the way of the devices that apply the heads to the can-body. Said arm or support b has stops or projections b' , which retain the can-body in place and prevent it from moving endwise. The clamps $c c$ are semicircular and are arranged at opposite sides of the point where the can-body is supported by the arm b , said clamps

being attached to the upper ends of levers $d d$, the lower ends of which are pivoted upon the rod e .

f represents a driving-shaft journaled in bearings in the supporting-frame and provided with a series of cams whereby motion is given to the different parts of the machine. The can-supporting arm b has a trundle-roll b'' , which is engaged with a cam-groove g' in a disk g on the shaft f , and is thereby given an oscillating motion, as described. The levers $d d$ are provided with trundle-rolls which enter cam-grooves h' in disks $h h$ on the shaft f , said cam-grooves being formed to move the levers $d d$ and the clamps $c c$ thereon alternately toward and from each other, thus closing the clamps upon a can-body, as shown in Fig. 4, while said body is supported by the arm b , the cams being timed to hold said clamps upon the can-body while the heads are being applied thereto, and to then separate the clamps and allow the headed body to drop into a chute i , through which the can-bodies pass from the machine to another machine or floater which solders the heads. The cans are released from the chute a one at a time by a feeding mechanism composed of two slides or arms $A A'$, which project in opposite directions into slots $D D'$ in said chute, and are connected to a shank or holder B , which is attached to the upper end of a lever C . Said lever is mounted to swing upon the rod e , and has a trundle-roll F , which enters a cam-groove G in a disk H on the shaft f . The rotation of said disk oscillates the lever C and causes it to reciprocate the slides $A A'$, and thereby simultaneously move one slide into and the other out of the chute a . Said slides are separated by a space about equal to the diameter of one can-body, and when the lower slide A' is moved out from the chute the can-body thereon is released and allowed to drop, the slide A being at the same time moved inwardly to arrest the next can-body above. After the discharge of the can-body the slides $A A'$ are moved in the opposite direction, the slide A' being thus moved into the chute to arrest the lower can-body, which is allowed to fall upon it by the outward movement of the slide A .

$j j$ represent holders or carriers located at

opposite ends of the clamps *c c*, each holder having connected to it by bolts or pivots *k k* two levers *m m*, having jaws *m' m'* formed on their outer ends. Said jaws are semicircular 5 and project over the inner ends of the holders *j*. A slot *o* is formed in the holder *j* behind the jaws *m'*, to permit the insertion of the flanged can-head behind the jaws. Means are provided for opening and closing the 10 jaws, as hereinafter described, and when the jaws are closed their edges coincide with the inner surface of the flange of the can-head, so that the can-head cannot pass through the circular opening between the jaws *m'*. In 15 each holder *j* is a cavity *p*, communicating with the slot *o*, said cavity receiving the can-head dropped through said slot. In the cavity *p* is a plunger or follower *q*, which is normally forced forward by a spring *v*, the purpose of which will be hereinafter explained. Said plunger *q* is attached to the rod *r*, which passes through the holder *j*, and is adapted 20 to slide longitudinally in said holder, and in a guide *s'*, which is formed on a swinging frame *s*, and is fitted to move vertically in a 25 slot *t* in an arm *u*, formed on a slide *w*, which slide is fitted to move between guides *y y* on the supporting-frame. On said slide are arms 2, to which are pivoted at 3 arms 4, formed on 30 the swinging frame *s*. The holder *j* is fitted in a socket in the frame *s*, and said frame, with the slide *w*, is moved longitudinally to carry the holder *j* and its jaws *m' m'* toward and from the can-body, held by the clamps *c*, by 35 a cam 41 on the shaft *f*, said cam receiving a trundle-roll 5, supported by an arm 26 on said slide. In addition to its longitudinal movement, the frame *s* has an oscillating movement on the center or pivot 3, said 40 movement being imparted by means of a vertical connecting-rod 6 and a cam-groove 7 in a disk 8, attached to the shaft *f*, said rod 6 being fitted to slide in guides 9, attached to the supporting-frame. The rod 6 is pivoted 45 to a collar 6', in which the rod *r* is free to slide lengthwise. The rotation of the cam 8 causes the rod 6 to alternately raise and lower the outer end of the rod *r*. It will be seen, therefore, that when the outer end of 50 the rod *r* is lowered the jaw-carrier will be inclined, so that the can-head therein will be inclined from a vertical position, its upper portion being thrown outwardly farther from the end of the can-body to which it is to be applied than its lower portion, while the upward movement of the rod *r* will restore the can-head to a vertical position. The described movements of the rod *r* are so timed that 55 when the slide *w* is moved outwardly to carry 60 the jaws away from the can-body the outer end of the rod *r* is depressed to give the described inclination to the can-head, and when the slide *w* is moved in the opposite direction to carry the jaws toward the can-body 65 the outward end of the rod *r* will remain depressed until the lower portion of the flange of the can-head comes to a bearing on the

corresponding point of the can-body, after which the outer end of the rod *r* is raised, thus bringing the jaws and can-head to a vertical 70 position and completing the application of the flanged head to the end of the can-body. The head is thus brought gradually to a bearing on the end of the body, the movement being similar to that employed in applying a flanged 75 head or cover to a cylindrical box or can by hand, so that the head is more easily and certainly applied than it would be if held parallel with the end of the can-head when first presented thereto. The office of the plunger 80 *q* is to support the can-head with a yielding pressure against the jaws *m'* while the head is being applied to the can-body, the spring *v* normally pressing the plunger forward and permitting it to yield slightly, so that in case 85 there is any unusual resistance to the application of the can-head to the body, caused by imperfections in the flange of the can-head or otherwise, the plunger *q* will yield, and thus prevent breakage of or injury to the 90 parts through which the head-applying pressure is exerted and imparted.

The plunger is thrown back from the jaws to permit the insertion of a can-head while the jaws are receding by means of a lever 12, 95 which is pivoted at 13 to ears on the slide *w* and bears at its upper end against a collar 14 on the rod *r*. The lower end of said lever projects below the slide *w* and is provided with an adjustable screw or stud, which, when 100 the slide *w* is moving backwardly, strikes the fixed supporting-frame, the lever 12 being thereby turned on its fulcrum and caused to give the rod *r* and plunger *q* an independent backward movement. While the plunger is 105 thus held back a can-head is dropped into the cavity *p* through the slot *o*, and when the slide *w* in moving forward to carry the jaws toward the can-body removes the lever 12 from contact with the supporting-frame the 110 spring *v* forces the rod *r* and plunger *q* forward and causes the plunger to hold the can-head flange against the closed jaws *m'*. Said jaws remain closed during the application of the can-head to the can-body, their inner 115 edges being flush with the inner surface of the can-head flange, so that they closely embrace the can-body when moved forward. The jaws are opened after the can-head is applied to the body by means of a plate 15, 120 fitted to rotate on the carrier *j*, and provided with cam-grooves 16 16, Fig. 2, which receive the rear ends of the jaw-levers *m*. Said plate 15 has a slot 17, which receives a stud 18 on a lever 19, which is pivoted at 20 to the supporting-frame, and has at its lower end a trundle-roll 21, which enters a cam-groove 22 in a disk 23 on the shaft *f*. The rotation of the disk 23 causes the lever 19 to oscillate, and in turn to oscillate the plate 15, the cam-grooves 16 16 being thus caused to move the levers *m m*, and thereby open or close the jaws *m' m'*, as the case may be. The jaws are opened just before the carrier *j* is moved 130

outwardly away from the can-body, and are closed immediately after they have passed away from the can-head flange, so that they are in position to hold the flange of the next 5 can-head in the manner already described.

The general operation of the machine is as follows, it being understood that in the organized machine there are two of the can-head-applying mechanisms above described, both 10 operating simultaneously, so that both ends or heads are applied to the can-body at once. A can-body is first dropped on the supporting-arm *b* from the chute while the clamps *c c* and the holders *j j* are at the outward extremes of their movement. The clamps *c c* are then moved inwardly and caused to grasp the can-body, after which the supporting-arm *b* is moved to one side and the holders *j j* advance in their inclined positions and present 15 the lower portions of the can-heads to the can-body held by the clamps *c c*, and are then made horizontal by the upward movement of the rod *r*, thereby completing the application of the can-heads, the jaws being then opened 20 and the holders *j* moved back, as already described. After the jaws have receded from the can the clamps *c c* are opened and the can drops therefrom into the discharge-chute *i*.

Parts of the machine hereinbefore described 25 are shown and claimed in three other applications filed by me concurrently herewith—viz., the can-body supplying or letting-off devices and the clamps that hold the can-bodies while they are being headed in application 30 Serial No. 300,250; the head-holding jaws in application Serial No. 300,248, and the mechanism for applying the can-heads to the can-bodies in application Serial No. 300,247.

I claim—

40 1. In a can-heading machine, the combination of can-body supplying or feeding devices, duplicate reciprocating and tilting can-head holders for simultaneously presenting two can-heads to a can-body, means for holding a can-body while the heads are being applied, a driving-shaft having a series of cams, and intermediate connections whereby the proper movements are imparted to said devices and holders from said cams, substantially as set forth.

45 2. The combination of the can-body clamps, a support to arrest a can-body in position to be grasped by said clamps, the reciprocating and tilting can-head holders *j j*, having the 50 can-head holding and releasing devices, the driving-shaft having the operating-cams, and

the intermediate mechanism, substantially as described, whereby motion is communicated from said cams to the said support, clamps, and head holding and releasing devices, as 55 set forth.

3. The combination of the can-body-supplying chute, the reciprocating slides therein, the lever *C*, supporting said slides, the can-body-supporting arm *b* under said chute, the 60 body-clamps *c c*, the levers *d d*, supporting said clamps, the head-holders *j j*, having head-clamping jaws, substantially as described, the levers 19 19, to operate said jaws, the slides *w w*, supporting said holders and 65 clamping devices, and the driving-shaft *f*, having the cams engaged, respectively, with the arm *b*, levers *d d*, slides *w w*, and levers 19 19, as set forth.

4. The combination of the can-supplying 70 chute *a*, the delivering-chute *i*, the clamps *c c* between said chutes, the levers *d d*, supporting said clamps, the body-supporting arm or lever *b*, arranged to arrest a can-body between the clamps, the head-holders *j j*, having head-clamping jaws, substantially as described, the levers 19 19, to operate said jaws, the slides *w w*, supporting said holders and 75 clamping devices, and the driving-shaft *f*, having the cams engaged, respectively, with the arm *b*, levers *d d*, slides *w w*, and levers 80 19 19, as set forth.

5. In a can-heading machine, the combination of the can-body-holding clamps, a reciprocating and tilting head holder or carrier 85 having a head-receiving cavity and movable jaws arranged to bear against the edge of a can-head flange in said cavity, mechanism, substantially as described, for opening and closing said clamps and jaws, and mechanism for operating the carrier and its jaws, as 90 set forth.

6. In a can-heading machine, the combination, with a can-body-holding device, of a reciprocating and tilting can-head carrier 95 adapted to apply first one edge and then the other edge of a can-head to a can-body, substantially as set forth.

In testimony whereof I have signed my name to this specification, in the presence of two subscribing witnesses, this 31st day of January, 100 A. D. 1889.

EDWIN E. ANGELL.
